Primary Examiner—Catherine E. Kemper
Attorney, Agent, or Firm—George H. Riches[57] **CLAIM**

The ornamental design for a film font clip for use in securing a flexible font to a character drum, substantially as shown and described.

DESCRIPTION

FIG. 1 is an exploded top plan view of a film font clip for use in securing a flexible font to a character drum showing my new design;

FIG. 2 is an exploded front perspective view thereof; FIG. 3 is a top plan view thereof, with a flexible font shown in broken lines for illustrative purposes only and forming no part of the claimed design;

FIG. 4 is a front perspective view thereof, with a flexible font and a character drum shown in broken lines for illustrative purposes only and forming no part of the claimed design.

FIG.1.

FIG.2.

FIG.3.

FIG.4.
